(57) **CLAIM**

The ornamental design for an irrigator for large intestine, as shown and described.

DESCRIPTION

FIG. 1 is a perspective view of an irrigator for large intestine showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view thereof, with the connecting tube and tank shown in broken line for the purpose of illustrating only and forms no part of the claimed design.
